[57] CLAIM

The ornamental design for a combined hand held keyboard and display terminal and optical scanning head, as shown and described.

DESCRIPTION

FIG. 1 is a top front, right side, perspective view of a combined hand held keyboard and display terminal and optical scanning head showing our new design;

FIG. 2 is a front elevational view thereof on an enlarged scale;

FIG. 3 is a top plan view thereof on an enlarged scale;

FIG. 4 is a right side elevational view thereof on an enlarged scale;

FIG. 5 is a rear elevational view thereof on an enlarged scale;

FIG. 6 is a left side elevational view thereof on an enlarged scale;

FIG. 7 is a bottom plan view thereof on an enlarged scale;

FIG. 8 is a top front, left side, perspective view of the design with the detachable scanning head repositioned to face left;

FIG. 9 is a rear elevational view thereof on an enlarged scale.
